TREATMENT OF CELLULOSE DERIVATIVES

Edward Kinsella, Joshua Bower, John Frederick Briggs, and Robert Pierce Roberts, Spondon, near Derby, England, assignors to Celanese Corporation of America, a corporation of Delaware

Application September 30, 1930, Serial No. 485,410
In Great Britain October 7, 1929

4 Claims. (Cl. 18—8)

This invention relates to the manufacture of artificial silk and other filaments or threads from solutions of cellulose acetate or other cellulose derivatives, particularly by the dry or evaporative method, and is an improvement in or modification of the invention described in U. S. application No. 382,907 filed August 2nd, 1929.

According to a process for the production of artificial filaments or threads described in the 10 said specification, a spinning solution is extruded into a spinning cell or chamber through which flows an evaporative medium in counter-current to the direction of flow of the filaments or threads and an additional evaporative medium is introduced into the said current in the vicinity of the jet. The additional medium is preferably directed 15 towards the filaments as they issue from the jet.

The introduction of evaporative medium in this 20 manner enables the uniformity and character of the filaments or threads to be controlled to a high degree.

The present invention has for its object to 25 enable evaporative medium so introduced to be brought into even closer proximity to the filaments issuing from the spinning jet. It will be understood that where, for example, a line jet is employed no difficulty is experienced in projecting, according to the prior invention, evaporative 30 medium on to the filaments from both sides. In the case, however, of jets having their spinning orifices arranged in the form of rings or other closed or partially closed figures the evaporative medium can only be directed towards the outside 35 of the circular, part-circular, or similar bundle of filaments when the medium is introduced by devices having a discharge orifice or orifices disposed outside the bundle of filaments.

According to one feature of the present invention 40 the additional medium is introduced to the inside of a bundle of filaments in the vicinity of the spinning jet. The whole of the additional medium may be introduced into the cell in this manner, or such introduction may be used in conjunction with the introduction of additional medium to the outside of the bundle of filaments.

In one method of carrying out this feature 45 of the invention, the additional medium is introduced through the plane of the jet. Thus, the disc-type jet commonly employed may be replaced by an annular jet, the central hole of which serves as an inlet for the additional medium or through which a pipe or jet for introducing the additional medium can pass to the 50 interior of the filament bundle. Ring jets may

also be employed, the central opening of the jet readily permitting the introduction of the additional medium in any desired manner.

A further method of carrying out the introduction consists in employing a spinning jet in 5 which instead of a complete circle or closed figure of orifices a partially closed circle or figure is employed. A gap is thus left in the bundle of filaments as they are spun from the jet and through this gap there is inserted a pipe or jet by means 10 of which evaporative medium is directed to the inside of the bundle. The pipe or jet may be slid or swung into position after extrusion of the filaments has commenced, a stop being provided to control the position of the pipe or jet inside the 15 bundle. A spring catch may be fitted to secure the pipe or jet in place, or other means may be adopted for the same purpose.

The medium introduced by the pipe or jet may 20 be directed in any desired direction with respect to the filaments, for example, downwardly, upwardly, or radially outwards, but preferably in the direction of movement of the filaments and somewhat outwardly.

A further feature of the invention consists in 25 constraining the additional medium introduced into the cell or chamber in such a way that it is caused to flow through a tubular or other collector device that surrounds the filaments, the additional medium thus being brought into intimate 30 contact with the filaments. The flow of the additional medium through the collector device may be in the same direction as that in which the filaments are moving, or opposite thereto, the position of the device for introducing the medium 35 with respect to the collector device and the manner in which the device discharges the medium being so arranged as to assist the flow of the medium in the desired direction.

The invention is applicable to any dry spinning 40 process in which the evaporative medium flows in counter-current to the filaments. For example, it may be used in connection with dry spinning processes in which spinning solution is extruded downwardly into an upwardly moving 45 current of evaporative medium, or upwardly into a downwardly moving current.

The amount of additional evaporative medium 50 introduced may bear any desired relationship to the total volume of evaporative medium passing through the cell. In order that this proportion may be regulated, it is preferred that the pipe, tube, conduit, or other means employed for supplying the additional medium should be provided with control means, such as are described in 55

U. S. Patent No. 1,541,104 with reference to the draw-off from the cells. The draw-off from the cells is preferably controlled in a similar manner, and where an installation comprises a number of 5 cells or chambers, each should be fitted with control means for the supply of additional medium, and for the draw-off, so that all the cells may operate under similar uniform conditions. By means of the close control described, the additional medium may be introduced in relatively 10 small or relatively large proportions.

The medium introduced into the vicinity of the jets may be heated before its introduction, and any suitable means may be employed to impart the desired degree of heat thereto, but, on 15 the other hand, cold or comparatively cold medium may be introduced into the cell if desired.

If desired the additional evaporative medium may contain a proportion of solvent or other 20 vapours, introduced for example by simple admixture therewith, or by passing the medium through a moistening chamber or by mixing it with solvent laden medium, for example, solvent laden medium withdrawn from the cell.

25 The invention will now be described in greater detail with reference to the accompanying drawings, but it is to be understood that this description is given by way of example only and is in no respect limitative.

30 Fig. 1 is an elevation, partly in section, of a spinning jet fitted with means for introducing additional medium inside the bundle of filaments;

Fig. 2 is a diagonal section of part of the jet; and

35 Fig. 3 is a plan view.

Fig. 4 is a sectional view of a spinning cabinet showing the jet in operation.

Fig. 5 is an elevation of a further form of 40 means for introducing additional medium to the inside of the bundle of filaments; and

Fig. 6 is a view from beneath of the spinning jet shown in Fig. 5.

Figs. 7, 8 and 9 are sectional views of spinning cells in which the means for introducing additional medium are used in conjunction with collector devices surrounding the filaments.

Referring to Figs. 1-4, a spinning jet comprises a square body 7, the lower part 8 of which is cylindrical in shape and screw threaded. A cylindrical space 9 in the body to which spinning solution is supplied communicates by means of four passages 10 with an annular space 11 on the lower face of the body 7. Into a central recess 12 in the lower face of the body 7 is fitted a member 13 which is held in place by means of set screws 14. Against the face of the jet body 7 are placed a piece of filter cloth 15 and an annular jet 16, together with suitable packing 17. The holes 18 in the annular jet fall under the annular space 11 in the jet body 7. The jet 16, together with the packing and filter cloth, is held in place by a nut 19, screwed on to the lower half 8 of the jet body 7, and by a member 20 passing through the centre of the jet and screwed in to the member 13. The member 20 is provided with hexagon faces 21 so that it may readily be gripped for screwing in place.

The spinning solution is supplied under pressure to the space 9 and passes down the passages 70 10 to the annular space 11 and through the filter cloth 15, emerging from the orifices 18 in the annular jet 16 in the form of a circular bundle of filaments 31 completely surrounding the member 20.

75 Referring to Fig. 2, the recess 12 communi-

cates by means of an oblique passage 22 with a pipe 23 connected to a source of air under pressure. The air passes to the recess 12 and down a passage 24 in the member 20, then spreading over a cone shaped part 25 of the member 20 to pass out uniformly from all sides of the member 20 to the inside of the bundle of filaments 31, its passage being controlled and directed by an adjustable spreader 26, screwed into the member 20. The air emerges in a downward and outward direction, as shown by the arrows in Figure 4. The whole jet is attached by means of screw-threads 27 to the spinning solution supply pipe 28 in the spinning cabinet 29.

Referring to Figs. 5 and 6, a disc jet 36 secured 15 to a nut 35 by a nut 37 has a number of orifices 38 disposed in the form of a horse shoe, thus causing a gap to be formed on one side of the bundle of filaments 31. To the supply pipe 28 is secured an attachment 39 adapted to support a 20 clip 40 carrying an air pipe 41 to which air is supplied through a flexible connection 42. The clip 40 swings about a pivot 43, a lug 44 on the part 46 limiting the clockwise movement of the clip and pipe. Attached to the end of the pipe 41 is an air jet 45, the pipe 41 being so bent, that when the pipe is in its operative position as limited by the lug 44, the air jet 45 is surrounded by the filaments 31 issuing from the jet orifices 38. Air supplied to the pipe 41 emerges through a series of holes in the jet 45 to the inside of the bundle of filaments. When the pipe 41 is swung back the air jet 45 passes through the gap 46 in the filaments 31, and the pipe and jet assume the inoperative position shown in dotted lines. 30

In Fig. 7 a jet of the form illustrated in Figs. 1-4 is shown in use with a cylindrical collector device 48 surrounding the whole of the jet, so that the air passing up the cell in counter-current to the filaments is constrained by the device 48 and a supporting diaphragm 49 to pass through the vicinity of the jet before reaching the draw-off pipe 50 by means of which it is removed from the cell. The collector 48 also constrains the additional air to flow in intimate contact with the filaments. Further additional air may be introduced into the cell by means of perforated ring 53.

Fig. 8 shows a similar collector device 48 used in conjunction with a plain jet 51, additional air being supplied by a pipe 52 and perforated ring 53 which entirely surrounds the filaments. The position of the orifices 54 in the ring 53 is such that the air is directed upwards and inwards, so that the air flows through the collector 48 in close contact with the filaments. 55

Fig. 9 shows a collector device 56 depending from the filter 30 and surrounding the jet. An air supply pipe 57 and perforated ring 58 supply a downward current of air from just above the jet, the said current passing down the collector 56 in intimate contact with the filaments before joining the counter-current of air which is proceeding to the draw-off pipe 50.

Any of the devices introducing additional medium inside the bundle of filaments, as illustrated in Figs. 1-7 may be used in conjunction with devices for supplying additional medium outside the filaments, such an arrangement being shown in Fig. 7, in which a perforated ring 53 is shown 70 for supplying air to the outside of the bundle of filaments 31 in addition to the air supplied inside the bundle.

What we claim and desire to secure by Letters Patent is:-

1. Process for the production of artificial filaments from solutions of cellulose derivatives by the evaporative method, comprising extruding a solution as a bundle of filaments into an evaporative medium, said medium flowing in counter-current to the direction of the bundle of filaments, and introducing additional evaporative medium inside the bundle of filaments from behind the point of extrusion.
- 10 2. Process for the production of artificial filaments from solutions of cellulose derivatives by the evaporative method, comprising extruding a solution as a bundle of filaments into an evaporative medium, said medium flowing in counter-current to the direction of extrusion of the bundle of filaments, and introducing additional evaporative medium in the vicinity of the point of extrusion, both inside and outside of the bundle of filaments.
- 15 3. Dry-spinning apparatus for the production of artificial filaments, comprising a spinning chamber, a spinning jet adapted to extrude a bundle of filaments into said chamber, means

adapted to draw an evaporative medium through said chamber in counter-current to the direction of extrusion of the bundle of filaments from the jet, and means for introducing additional evaporative medium in the vicinity of the jet, both inside and outside the bundle of filaments.

5 4. Dry-spinning apparatus for the production of artificial filaments, comprising a spinning chamber, a spinning jet adapted to extrude a bundle of filaments into said chamber, means 10 adapted to draw an evaporative medium through said chamber in counter-current to the direction of extrusion of the bundle of filaments from the jet means for introducing additional evaporative medium both inside and outside the bundle of 15 filaments in the vicinity of the jet, and means adapted to constrain the additional evaporative medium to maintain intimate contact with the filaments.
